(57) **CLAIM**

We claim the ornamental design for an electrophoresis device, as shown and described.

DESCRIPTION

FIG. 1 is a perspective view of an electrophoresis device showing our new design;

FIG. 2 is a front elevational view;

FIG. 3 is a side elevational view with the top closed, the opposite side elevational view being a mirror image thereof; FIG. 4 is a side elevational view with the top open, the opposite side elevational view being a mirror image thereof; and,

FIG. 5 is a back elevational view.

The broken lines are for illustrative purposes only and form no part of the claimed design.

The bottom of the electrophoresis device is not visible during normal use.
